(57) **CLAIM**

The ornamental design for a wall transmitter, as shown and described.

DESCRIPTION

FIG. 1 is a front right top perspective view of a wall transmitter.

FIG. 2 is a top view thereof.

FIG. 3 is a bottom view thereof.

FIG. 4 is a left view thereof.

FIG. 5 is a right view thereof.

FIG. 6 is a rear view thereof; and,

FIG. 7 is a front view thereof.

The broken lines illustrate portions of the wall transmitter that form no part of the claimed design.
